UNITED STATES PATENT OFFICE.

JOHN GUIRY, OF NEW YORK, N. Y.

DUMPING-SCOW.

No. 807,552.

Specification of Letters Patent.

Patented Dec. 19, 1905.

Application filed July 30, 1904. Serial No. 218,848.

To all whom it may concern:

Be it known that I, JOHN GUIRY, a citizen of the United States, and a resident of New York city, in the county of New York and State 5 of New York, have invented certain new and useful Improvements in Dumping-Scows, of which the following is a specification.

The invention relates to improvements in dumping-scows; and it consists in the novel 10 features and combinations of parts hereinafter described, and particularly pointed out in the claims.

The scow of my invention comprises two suitably-separated pontoons connected together by a deck, a longitudinal series of bins 15 or hoppers arranged upon the scow and disposed between the vertical planes of the facing sides of said pontoons, a horizontally and longitudinally sliding gate for the bottoms of 20 said bins or hoppers, and means for operating said gate, said bins or hoppers at their front and rear inner lower portions having inclined or converging walls and said gate having a series of openings adapted at the proper 25 time to register with the lower ends of said bins or hoppers, so as to permit the discharge of the refuse downwardly between said pontoons. The aforesaid sliding gate will when in one position close the lower ends of the 30 bins or hoppers, so that the latter may be filled, and when moved from such position said gate will carry its discharge-openings below said bins or hoppers, and at such time the refuse may at once escape downwardly.

35 The object of my invention is to produce a very durable and easily-operated scow and one lacking the disadvantages and complexity of scows at present in use having hinged doors at the bottom of the refuse-receptacles.

40 The invention will be fully understood from the detailed description hereinafter presented, reference being had to the accompanying drawings, in which—

Figure 1 is a top view, partly broken away, 45 of a scow constructed in accordance with and embodying the invention. Fig. 2 is a central vertical longitudinal section of same on the dotted line 2 2 of Fig. 1. Fig. 3 is a vertical transverse section of same on dotted line 3 3 50 of Fig. 2; and Fig. 4 is a detached top view, partly broken away, of same with the bins or hoppers removed, Fig. 4 being presented to illustrate more clearly the construction of the sliding gate.

55 In the drawings, 10 and 11 designate the two pontoons, which are connected at their forward

ends by a deck 12 and at their rear ends by a deck 14, while at their middle portions the said pontoons are connected together by transverse beams 15, upon which are supported the 60 longitudinal grooved rails 16 for the series of ball-bearings 17. (Shown more clearly in Figs. 3 and 4.)

Upon the ball-bearings 17 is placed the sliding gate 18, containing a series of equidistant 65 openings 19 and solid portions 20. The gate 18 in the employment of the scow is given a longitudinal sliding motion upon the ball-bearings 17 by means presently to be described. The solid portions 20 of the gate 18 are connected in series by longitudinal bars 21, Fig. 4, which are disposed over the rails 16 and prevent refuse passing through the openings 19 from accumulating upon the rails 16.

Above the sliding gate 18 and over the 75 space between the pontoons 10 11 is mounted the longitudinal series of bins or hoppers 22, formed by the sides 23 23 and partitions 24, the bins 22 being equally spaced and independent of one another and each at its lower 80 inner front and rear portions having the inclines 25 26, converging downwardly and leaving an opening in the lower end of the bin corresponding in size to one of the openings 19 in the gate 18. The series of bins 22 85 are set downwardly into the space between the upper portions of the pontoons 10 and 11 and are supported upon said pontoons by means of shoulders 27, Fig. 3, formed on the sides 23 and engaging the upper inner edges 90 of said pontoons. The lower edges of the series of bins 22 are in close relation to the upper surface of the gate 18, but do not bear upon said gate, the latter being thus left free to be moved longitudinally below the 95 bins 22 and upon the ball-bearings 17. The inclines 25 26 direct the refuse downwardly through the open lower ends of the bins 22 when the gate 18 is in such position that its 100 openings 19 are in line with the lower ends of said bins, and when the gate 18 has been shifted to carry its solid portions 20 below the lower ends of the bins 22 the openings in said gate are closed by the thickness afforded by the adjacent inclines 26 25, as shown in Fig. 105 2, the distance between the outer lower edges of said inclines 26 25 being equal to the openings 19 and also substantially equal to the width of the solid portions 20 of said gate 18.

When the gate 18 has its solid portions 20 110 below the bins or hoppers 22, the latter may be filled with refuse, and the openings 19 of

said gate will be concealed and closed by the adjacent inclines 26 25, and when the gate 18 has been moved longitudinally toward the rear the openings 19 will appear below the open 5 lower ends of the bins 22 and the solid portions 20 of said gate will pass below the adjacent inclines 26 25, and thus be prevented from obstructing the outflow of the refuse from said bins.

10 Upon the forward and rear decks 12 14 are mounted in suitable bearings the transverse shafts 28 29, upon which are secured the winding-drums 30 31, to which are respectively connected chains 32 33, which chains are also 15 respectively connected to the front and rear ends of the gate 18 and are utilized for imparting to said gate its longitudinal sliding movement, the drums 30 paying out the chains 32 when the drums 31 are winding up the 20 chains 33 and the drums 31 paying out the chains 33 when the drums 30 are winding up the chains 32. The shafts 28 29 and drums 30 31 have simultaneous rotation imparted to them by means of the sprocket-chain 34 and 25 sprocket-wheels 35 through the medium of the pinion-wheels 36, short shafts 37, and gear-wheels 38, said gear-wheels 38 being fixed upon the shafts 28 29 and in constant mesh with the pinion-wheels 36, which are 30 rigid upon the short shafts 37, carrying the sprocket-wheels 35. The sprocket-chain 34 may be set in motion by any convenient means or power, and in the present instance I illustrate a crank 39, applied to the shaft of 35 the rear sprocket-wheel 35 for rotating said wheel in either direction and causing the movement of the sprocket-chain 34 in either direction in accordance with the direction of movement it is desired to impart to the gate 18.

40 In Fig. 1 I illustrate the gate 18 as having been moved rearwardly so as to carry its openings 19 below the lower ends of the bins or hoppers 22 for the purpose of permitting the discharge of the refuse through said openings. When it is desired to close the lower ends of the bins 22, the crank 39 will be operated to drive the upper reach of the chain 34 forwardly, and at such time the shaft 28 having been set in motion the drums 30 will 45 wind upon themselves the chains 32 and draw the gate 18 forwardly to the position in which said gate is illustrated in Fig. 2, the solid portions 20 of said gate then closing the lower ends of the bins 22 and the said openings 19 being below the adjacent inclines 26 25. When during the rotation of the forward shaft 28 the gate 18 is pulled forwardly, the drums 31 will pay out the chains 33 in the same proportion that the chains 32 are wound upon 50 the drums 30. After the bins 22 have been filled and the scow has reached the place at which the refuse is to be discharged a reverse motion will be imparted to the sprocket-chain 34, its upper reach being then caused to travel 55 rearwardly, with the result of causing the

drums 31 to wind upon themselves the chains 33 and draw the gate 18 rearwardly into the position in which said gate is illustrated in Fig. 1, the solid portions 20 of the gate then passing below the adjacent inclines 26 25 and 60 the openings 19 of said gate passing into register with the then opened lower ends of the said bins or hoppers.

One advantage of my invention is that the discharge from the bins or hoppers 22 will 65 commence as soon as the gate 18 is set in motion in a rearwardly direction, and a further advantage of the construction presented by me is that the bins may discharge their contents in shallow water, if necessary, there being no hinged doors to be swung outwardly below said bins. It is my purpose that the sliding gate 18 shall be above the water-line, and hence in the operation of the gate the latter does not reach the water and a space is 70 provided above the water-line for the discharge of the refuse. If, however, the load placed into the bins 22 should be such that the gate 18 should pass below the water-line, it may be operated with entire convenience; 75 but my purpose is to have said gate clear of the water. There are many well-recognized disadvantages in the employment of dumping-scows having hinged doors at the bottoms of 80 the refuse-receptacles, and these disadvantages are entirely obviated by my invention.

Below the front incline 25 of the forward bin 22 is provided a stop 40, against which the forward end of the gate 18 may abut when said gate is in its forward position, (shown in 100 Fig. 2,) this stop assuring the arrest of the openings 19 below the adjacent inclines 26 25.

What I claim as my invention, and desire to secure by Letters Patent, is—

1. A scow comprising the connected pontoons, and the longitudinal series of bins thereon adapted to discharge between said pontoons, combined with the longitudinally-arranged sliding gate 18 having solid portions 20 and containing the openings 19, longitudinal rails 105 for supporting said gate upon said pontoons and below said bins, and means for moving said gate longitudinally, the said solid portions 20 forming the bottoms for said bins when said gate is in one position and said openings 110 19 passing below said bins when said gate is moved to its other position to carry said solid portions from below said bins; substantially as and for the purposes set forth.

2. A scow comprising the connected pontoons, and the series of bins thereon adapted to discharge between said pontoons, said bins having the converging inclines at their lower inner front and rear portions, combined with the sliding gate below said bins having openings adapted to be moved into register with the lower ends of said bins, and means for sliding said gate, the said inclines being adapted to close said openings when the solid portions of said gate are in position to close the 115 120 125 130

lower ends of said bins; substantially as set forth.

3. A scow comprising the connected pontoons, and the longitudinal series of equally-spaced bins thereon adapted to discharge between said pontoons, said bins having discharge-openings at their lower ends, and said openings being equally spaced, combined with the longitudinally-sliding gate below said bins having openings adapted to register with the said discharge-openings and also, when the gate is moved to close the lower ends of the bins, to register with the spaces between said discharge-openings, and means for sliding said gate; substantially as set forth.

4. A scow comprising the connected pontoons, and the series of bins thereon adapted to discharge between said pontoons, combined with the sliding gate adapted to form bottoms for said bins and having openings adapted, when the gate is moved for that purpose, to register with the lower ends of said bins, shafts at the ends of the scow and having winding-drums thereon, chains connected with said drums and said gate, and means for simul-

taneously rotating said shafts and drums and moving said gate; substantially as set forth.

5. A scow comprising the connected pontoons, and the series of bins thereon adapted to discharge between said pontoons, combined with the sliding gate adapted to form bottoms for said bins and having openings adapted, when the gate is moved for that purpose, to register with the lower ends of said bins, shafts at the ends of the scow and having winding-drums thereon, chains connected with said drums and said gate, sprocket-wheels connected to said shafts, and the sprocket-chain connecting said wheels for imparting simultaneous movement to said shafts and drums and moving said gate; substantially as set forth.

Signed at New York city, in the county of New York and State of New York, this 29th day of July, A. D. 1904.

JOHN GUIRY.
